ART OF GRINDING

George W. Binns, Cincinnati, Ohio, assignor to
Cincinnati Grinders Incorporated, Cincinnati,
Ohio, a corporation of Ohio

Application December 21, 1931, Serial No. 582,292

3 Claims. (Cl. 51—278)

This invention relates to improvements in the art of grinding and especially to improvements in a process or method of grinding.

An object of the invention is the provision of an improved process for accurately finishing tapered articles such as mushroom type valves and the like.

Another object of this invention is the provision of an improved process for finish grinding tapered valve seats and the like so that said valves seat throughout their area without being lapped or requiring the lapping in thereof.

A further object of the invention is the provision of an improved process for producing tapered valve seats free from chatter and other imperfections.

These and other objects are attained through the performance of the process diagrammatically depicted in the accompanying drawing and described in the following specification and it is to be understood that certain deviations may be made in the steps of the process as here described and illustrated within the scope of the appended claims without departing from or exceeding the spirit of the invention.

In the drawing:

Figure 1 is a diagrammatic elevational view of a mechanism for performing one step of the process.

Figure 2 is a top plan view of the structure shown in Figure 1.

Figure 3 is a diagrammatic elevational view of a mechanism for performing a subsequent step in the process.

Figure 4 is a top plan view of the structure shown in Figure 3.

Figure 5 is a view illustrating a part of the mechanism shown in Figures 3 and 4 as seen from line 5—5 of Figure 3 and forming a detail of the invention.

In the past it has been customary to grind tapered valve seats and the like at definite angles of inclination to the axis of a part integral therewith, such as the guiding stem of mushroom type valves. These faces or seats, however, frequently had imparted to them the out of roundness, chatter and other irregularities of either the said guiding stem, work support, chuck or other driving mechanism. This resulted in the necessity of either lapping the valve seat prior to use or grinding the said seat into the body of the valve or other part with which it is to be used. By the present process or method it has been found that tapered valve seats may be produced having a full seat and

requiring no further machining operation prior to their use. There has been chosen, and depicted in the drawing, the mushroom type of valve, as used in connection with internal combustion engines, to illustrate the various steps of the process, but it is to be understood that the process may be employed for grinding or finishing other types and kinds of work pieces.

The work piece 10 is first completely formed and its stem 11 finish ground to provide an axis of rotation, the valve seat 12 is then rough and semi-finished ground in any desirable manner and by any suitable process. It has been found, however, that if the work piece 10 is floated in the throat of a centerless grinder and the seat 12 then rough and semi-finished ground on a centerless grinder before the final finishing operation the valve is completed in an expeditious manner and at a minimum cost. The roughing and semi-finishing grinding operations are illustrated in Figures 1 and 2. As there shown, the centerless grinder comprises a work rest blade 13 having a supporting inclined face 14, inclining toward the active surface of a regulating wheel 15. The angled top 14 of the blade 13 with the operative face of the regulating wheel 15 form a work receiving trough in which the stem 11 of the work is placed. As will be noted from Figures 1 and 2, the axis of the work 10 and regulating wheel 15 are in parallel vertical planes but that the axis of the wheel 15 is canted or at an angle to the axis of the work whereby the said wheel exerts a feeding component on the work tending to axially shift same through the grinding throat. This movement of the work is arrested by a suitable stop 16 which engages the terminus of the stem 11.

In order to maintain proper frictional contact between the regulating wheel 15 and the stem 40 of the work, lateral or pressure rollers 17 are provided. These rollers 17 are mounted in the end of an arm 18 which is pivoted at 19 to a suitable support or bracket. The arm 18 is actuated in a clockwise direction by a spring 20 whereby 45 the rollers 17 yieldingly hold the work in engagement with the wheel 15.

It will be noted that the seat 12 is at an angle to the axis of the stem. Accordingly, there is provided a grinding wheel 21 rotatable about an axis which extends at the same angle to the axis of the work as the seat thereof. By this construction, a plane faced grinding wheel may be employed instead of a grinding wheel having a contoured or angled face thereon which presents 55

considerable difficulty in maintaining to the desired form.

The work piece is subjected to several grinding operations as above described which provide a reasonable finish thereon but which in order to be particularly useful must be lapped in or ground in to the part with which it is to be used. This may be caused partly by any chatter marks or out of roundness that may be in the stem 11 of the work. The same result is obtained if the work where mounted is a chuck or suspended between supporting centers which may allow the work to spring under the pressure of the grinding wheel. This invention contemplates instead of the use of a lapping operation, a grinding operation which is far more rapid and considerably less expensive than the lapping or intergrinding operation of the several parts. To this end the work piece is then placed in a second centerless grinder which likewise consists of a work rest blade or support 22 in close proximity to a regulating wheel 23. A grinding wheel 24 is also provided, rotatable about an axis disposed at an angle so as to place the plane face of the wheel parallel with the face to be formed on the work. It will be noted that the regulating wheel 23 is mounted for rotation about an axis extending parallel with the axis of the work instead of at an angle thereto as above described. From this it will be seen that the wheel 23 does not exert a feed component on the work but merely effects and controls its rotation. The work 10 is held in contact with the work rest blade or support 22 and wheel 23 by means of lateral or pressure rolls 25 in the same manner that the rollers 17 above described operate.

The work rest blade has secured to it a steady rest member 26 having a tapered seat 27 at one end thereof conforming contragenerically to the seat 12 formed on the work. This ring like seat 27 extends substantially entirely around the seat of the valve being broken away at 28 an amount just sufficient to permit access of the grinding wheel 24 with the said valve seat.

When the work reaches this stage of its manufacture, it is now necessary only to clean up the seat 12 by removing a very small amount of stock. For this reason no end stop is provided for the work since it has already been reduced to the desired length. However, the work piece is yieldably axially actuated relative to the grinding wheel and the steady rest seat 27 so that the work, while it is rotating, will maintain contact with the said steady rest seat 27 and the active face of the grinding wheel 24. For effecting this axial shifting of the work there is provided an end or terminal roller 29 rotatably carried by the end of an arm 30 pivoted at 31 to a fixed portion of the machine. A spring 32 has one end secured to the arm 30 and the other end to a fixed part of the machine which tends to oscillate the arm in a clockwise direction thereby shifting the work

to the right as seen in Figure 5 into the grinding contact with the grinding wheel 24.

The seat 27 in contacting with the work substantially throughout its length and breadth, except for the small area where it contacts with the wheel, effectively prevents any lateral or radial movement of the work and insures same rotating about a definite unvarying axis. This steadyng of the work prevents any chatter appearing in the seat so that a one hundred per cent seat is provided needing no further machining operation for producing a tight joint between itself and the part with which it is to cooperate. Furthermore, the steady rest seat prevents any previous chatter or imperfections in the stem of the work or driving parts of the machine from being transferred to and amplified on the seat of the work as was the case with prior processes.

What is claimed is:

1. The process of finishing the frustro-conical seat of a valve, or the like, consisting in spinning the frustro-conical seating surface of the valve against a contrageneric guide member engaging the major portion of said seating surface and abrading said seating surface with a high speed grinding member and positioning the operative portion of the grinding member substantially co-planar with the valve supporting surface.

2. The process of perfecting the operative seat of a frustro-conical valve head consisting in providing a contrageneric support member with a face for interfitting engagement with the face of the work, projecting a grinding member in interrupting relation with said face of the support and an operative portion forming a substantial continuation thereof, resiliently urging the valve against said combined seat whereby its positioning is entirely determined by interengagement therewith, effecting a spinning of the valve on its seat and a rotation of the grinding member at a speed in excess of the peripheral speed effected by spinning of the work whereby minute irregularities on the surface of the work are eliminated and a proper seating surface produced.

3. The process of producing a smooth seating face on a mushroom type valve or the like, consisting in forming a support for the seating face of the valve in part from an abrasive member and in part from a non-abrasive guide member, together engaging substantially the entire seating face, providing a clearance in the seating member for the valve stem whereby the member is supported entirely by engagement of its seating face with said parts, urging the valve into engagement with said seat, effecting a spinning of the valve on said combined seat and simultaneously effecting a high speed rotation of the abrasive portion of the seat for removal of surface irregularities from the valve.
